CLAIM

The ornamental design for a shoe, as shown and described.

DESCRIPTION

FIG. 1 is a side view of a shoe showing our new design; FIG. 2 is a rear perspective view thereof; FIG. 3 is a rear view thereof; FIG. 4 is an opposite side rear perspective view thereof; and, FIG. 5 is an opposite side view thereof.

The six broken line circles within the shaded area form no part of the claimed design. The broken line showing of the thin arcuate region within the shaded area represents a feature which forms no part of the claimed design. The broken lines depicting the remainder of the shoe form no part of the claimed design.
